BEDSTEAD ATTACHMENT
APPLICATION FILED JUNE 23, 1906

UNITED STATES PATENT OFFICE.

HORACE E. HENWOOD, OF NEW YORK, N. Y.

BEDSTEAD ATTACHMENT.

No. 852,508.

Specification of Letters Patent.

Patented May 7, 1907.

Application filed June 23, 1906. Serial No. 323,002.

To all whom it may concern:

Be it known that I, HORACE E. HENWOOD, a subject of the Crown of Great Britain, and a resident of the borough of Manhattan, city of New York, county and State of New York, have invented certain new and useful Improvements in Bedstead Attachments, of which the following is a specification, reference being had to the accompanying drawings, forming a part thereof.

My invention relates to bedstead attachments, and particularly to means adapted to be attached to an ordinary bedstead for converting the said bedstead into a hospital or invalid bed wherein the patient may be raised from the mattress or other supporting surface for whatsoever purposes may be necessary.

My invention comprises a stretcher, hoisting means therefor, and direction-pulleys, including clamps, by which the said pulleys may be attached to the desired parts of bedsteads of different sizes.

My invention consists not only in the general combination by which the said lifting mechanism may be employed for bedsteads of different sizes, but also in many details of construction in the lifting means, the direction-pulley supports and the stretcher.

My invention also consists in providing another opening, or other openings, in the fabric employed as the portion of the stretcher by which the invalid is supported, in addition to the opening usually employed therein for toilet purposes.

In order that my invention may be fully understood, I will now describe an embodiment thereof with reference to the accompanying drawings illustrating same, and will then point out the novel features in claims.

In the drawings, Figure 1 is a view in perspective of a bedstead with the attachments in position thereon. Fig. 2 is a face view of a clamp and roller employed. Fig. 3 is an end view of the same. Fig. 4 is a view in side elevation of winding means, and a clamp for connecting same to the bedstead posts. Fig. 5 is a top view of the same. Fig. 6 is a central vertical section therethrough. Fig. 7 is a detail view of the corner of the stretcher frame. Fig. 8 is a transverse sectional view therethrough upon the line 8-8 of Fig. 7. Fig. 9 is a detail view, partially in section, showing the hinge connection between the back rest frame and the stretcher frame. Fig. 10 is a detail view of a portion of the stretcher

frame, showing the opening through which the pivot of the back rest is inserted. Fig. 11 is a longitudinal sectional view of the upper end of the stretcher, and of the back rest when partially raised to support the patient. Fig. 12 is a detail view showing the pivotal connection between the strut which supports the back rest and the back rest frame.

The bedstead here shown is of the ordinary type of metal bedsteads comprising a head 15, a foot 16, and side irons 17. A mattress and spring 18 of ordinary form, such as the usual combined box spring and mattress, is shown as supported by the bed frame. The head 15 and foot 16 are each of the type having upper horizontal bars or heads 19, 20, and are also provided with the usual lower frame irons 21. This is an ordinary form of bed such as is well known in the market, and it is the purpose of my present invention that such a bedstead may be used in the ordinary manner by a member or members of a family, but that, when desired, such bedstead, by the addition of certain attachments, shall be readily converted into a hospital or invalid bed, so that an ordinary domestic bedstead may be converted at will, and with a minimum of trouble, into an invalid bed.

To these ends I provide a stretcher comprising a metallic frame 22, and a supporting fabric 23. The supporting frame 20 is composed of pipe lengths, which serve for the sides and ends thereof. The said sides and ends are connected together by corner pieces, one of which is illustrated fully in Fig. 7. Each of these corner pieces comprises an elbow 24, shouldered portions or abutments 25, and fingers 26 extending at right angles to each other from the said corner piece. These fingers, as will be clearly seen by reference to Fig. 7, are received within the ends of the pipe sections forming the side and end rods, the ends of the said pipe sections resting against the shoulders or abutments 25. I preferably provide slotted portions or grooves 27 in the fingers 26 for the purpose of receiving the shanks of buttons 28, which are screwed through the walls of the pipe sections for the purpose of receiving the ends of flexible lifting bands, to be presently described. These grooves or slots permit the shanks of the buttons 28 to be screwed in further than would otherwise be possible, so as to permit the buttons to have a further hold, and also serve to prevent the tube or pipe sections from turning with

respect to the corner pieces, when once the parts are secured together. This is important, as, if some such provision were not made, tension upon the lifting bands or straps would tend to turn the pipe sections, and cause the said lifting bands to become detached.

The fabric 23 is fastened to the frame in any suitable manner, preferably by lacing 29, as shown. The elbow part 24 of the corner piece may conveniently be provided with an eye portion 30, to which a portion of the lacing may be secured at the corners thereof, in order to hold the fabric firmly in its proper position. This stretcher is arranged normally to rest upon the mattress 18, and will not inconvenience the patient at all under such circumstances, as the only extra thickness is that of the fabric 23. The stretcher is arranged to be raised and lowered by means of flexible lifting bands or straps 31, 32, the free ends of which are connected to the stretcher frame by means of the buttons 28, the intermediate portions passing over suitable direction-pulleys, and the opposite ends of which are engaged by a winding bar or rod 33. The direction-pulleys are mounted in clamps 34, (shown in detail in Figs. 2 and 3,) by means of which they may be attached to any desired part of the bedstead. These clamps comprise two members 35, 36, secured together by bolts 37 and wing nuts 38. The lower ends of the members 35 and 36 surround a direction-pulley 39 supported thereby, portions of the said members constituting bearings for the trunnions of the said direction-pulley, and the upper ends of the said members 35 and 36 are curved, as is shown in the drawings, so that they will readily embrace the tubing constituting the bars 19 and 20 of the bedstead foot and head frames, and this portion of the members is so shaped, also, that the said clamp is equally adapted to be secured to the rails 21, as will be readily understood by reference to the drawings. Manipulation of the wing nuts 38 is all that is necessary to secure the clamps in position, either upon the tubing constituting the parts 19 and 20, or upon the rails 21, and, by reason of the fact that each clamp and roller 39 is a part independent of other clamps and rollers, the said devices may be attached at the desired points to bedsteads of different widths, sizes and shapes.

The winding mechanism comprises the member 33, above referred to, supporting clamps 40 and 41, and suitable gearing supported by the clamp 40. The clamp 40, and gearing in connection therewith, is illustrated fully in Figs. 4, 5 and 6, said clamp comprising two members 42, 43 secured together by means of bolts 44 and wing nuts 45, distance pieces 46 being employed to prevent the parts contained between the clamp mem-

bers on one side of the bolts 44 from being pinched. Upon the other side of the bolts 44, the members 42, 43, have parts 47, 48 arranged to embrace the posts 49 of the bedstead foot. Gearing, comprising a pinion 50 and a spur-gear 51, is arranged between the clamp members, the axles of said pinions being supported by the said clamp members. The axle of the pinion 50 has a projecting squared end to which may be attached an operating handle 52, while the axle of the spur-gear 51 is comprised in the winding bar or rod 33. This winding bar or rod is preferably tubular in form, and is provided with a slot 53 for receiving the lifting bands or straps 31, 32, such slot forming a means by which the strap ends are caused to be fastened to the winding bar or roller and positively rolled up upon the same when the said bar or roller is rotated. This rotation may be accomplished by rotation of the handle 52, motion being transmitted to the said winding bar or rod through the gearing 50, 51. A pawl 54 may be employed, if desired, to engage with the teeth of the pinion 50, thereby to act as a holding means to hold the parts in the position to which they have been moved. Rotation in the proper direction of the handle 52, and hence rotation of the winding bar 33, will result in lifting the stretcher to a position, such for instance as is shown in Fig. 1. In this position the patient will have been lifted to a position some distance above the mattress, as will be well understood, and, as the fabric 23 of the stretcher is provided with the usual opening 55, a vessel may now be placed upon the mattress 18 beneath the stretcher, for toilet purposes.

In order to give the patient greater comfort, I have provided a back rest 56 composed of a frame-work 57, and flexible fabric 58 secured thereto by lacing 59. The frame-work 57 comprises tube sections connected together by corner pieces 60, quite similar to the corner pieces employed for the main stretcher frame. To pivotally connect the side portions of the frame 57 with the stretcher frame, I have provided end members 61 (see particularly Fig. 9), said end members 61 provided with shanks 62 which extend inward within the ends of the pipe sections of the frame-work 57, and with trunnion pins 63 adapted to be received within openings 64 in the stretcher frame 22. The trunnions 63 are preferably provided with projections 65, which register with enlarged portions 66 of the opening 64, said projections 65 and enlarged portions 66 being so arranged axially with relation to each other as to only come in line in an unusual or a forced position of the back rest. Thus the back rest may be assembled into position with the stretcher frame, but will normally be held against accidental removal therefrom. A strut mem-

ber, comprising tubular sections 67 and a connecting member 68, is provided, the sections 67 being pivotally connected to the back rest frame 57 (see Fig. 12) in the same manner that the back rest frame is pivotally connected to the stretcher frame, the part 68 being arranged to coöperate with ratchet teeth 69 secured to the stretcher frame. The back rest may be swung up into the required position, and supported in position by the strut member, as will be well understood. If, then, the patient is well enough to be supported in a sitting position when elevated by the means above referred to for the foregoing purposes, the back rest may first be adjusted in the approved position. Then, to further promote the comfort and convenience of the patient, I have provided openings 70, in addition to the usual opening 55, in the fabric 23, through which the legs of the patient may be inserted, whereby the patient may be in an ordinary sitting position, and hence in a position best adapted to the requirements.

25 In a former United States Patent, No. 802,756, granted to me October 24th, 1905, an attachment was shown and illustrated adapted to be adjusted in position upon a bedstead, but such attachment was suitable only for a bedstead of a predetermined width. It will be apparent from the description and illustration herein that the present attachment is suitable for bedsteads of different widths, for the reason that the 35 clamps carrying the direction rollers are independent units, and may be adjusted upon a bedstead regardless of their relative positions. It is, of course, understood that for a wider bedstead a wider stretcher frame will be necessary, but it will be noticed that the only 40 change in even this part of the invention will be the provision of longer pipe sections for the end pieces of the stretcher frame, and a correspondingly longer pipe section for the 45 upper member of the back rest frame 57. It will also be understood that the novel feature comprised in the additional opening or openings in the stretcher fabric 23 is applicable to other forms of elevating devices, and that 50 such feature may, indeed, be employed wherever stretchers of this character are used for a corresponding purpose.

What I claim is:

1. Bedstead attachments comprising in 55 combination a stretcher, belts or straps

connected thereto, a plurality of attachable and detachable roller supporting clamps with independent rollers supported thereby, arranged to be clamped to various parts of a bedstead frame, the said rollers forming direction-pulleys for the said straps, and winding means for the straps, including a clamp composed of two parts adapted to be removably secured together, and having a portion shaped to fit the corner post of a bedstead, gearing comprising a pinion and a spur-gear mounted between the clamp members and journaled therein, said pinion having an axle arranged to receive the turning handle, and the axle of the spur-gear adapted to constitute winding means.

2. A bedstead attachment including a stretcher frame composed of pipe sections and corner pieces having members entering the ends of the said pipe sections, the members of the corner pieces having longitudinal recesses for receiving the shanks of studs or buttons, and studs or buttons fastened to the pipe sections and projecting into the said recesses.

3. A bedstead attachment comprising a clamp composed of two parts adapted to be removably secured together, and having a portion shaped to fit the posts of a bedstead, gearing comprising a pinion and a spur-gear 85 mounted between the clamp members and journaled therein, said pinion having an axle arranged to receive the turning handle, and the axle of the spur-gear adapted to constitute winding means.

4. A bedstead attachment including a stretcher frame, the side members of which are tubular, a back rest comprising side and end pipe sections, terminals for the side end sections comprising shanks arranged to be received within the pipe sections, and trunnion pins projecting at right angles thereto, said trunnion pins having lateral projections, and arranged to be received within openings in the tubular side elements of the stretcher 100 frame, said openings being substantially cylindrical, but having an enlargement to receive the said trunnion pin projection, the said enlargement and projections being so axially related to each other as to be normally out of register.

HORACE E. HENWOOD.
